Term of patent 14 years

(Cl. D64—11)

To all whom it may concern:

Be it known that I, Fritz Haseloff, a citizen of Germany, residing at Kassel, Germany, have invented a new, original, and ornamental Design for a Ticket Printing Machine or the like, of which the following is a specification, reference being had to the accompanying drawing, forming part thereof.

Fig. 1 is a perspective view of the ticket printing machine or the like showing my new design; and

Fig. 2 is a side elevational view thereof.

The left side of the apparatus has the same appearance as the right side and the back of the apparatus is plain and unornamented.

I claim:

The ornamental design for a ticket printing machine or the like, as shown and described.
